[57] ABSTRACT

A container is advanced by an arm or forked shifter guided by a reciprocating carriage or a crank driven by a motor. The drive motor is de-energized with the carriage in a position of such that the shifter is backed slightly away from the container. The shifter is then swung upward out of the container path and returned to its starting position. Alternatively a clutch may disengage the motor and crank at dead center and a compression or torsion spring effects backing off of the shifter from the container.

APPARATUS FOR SHIFTING CONTAINERS

This is a continuation of U.S. Pat. Ser. No. 742,828, now abandoned.

Containers are filled with fiber sliver by a continuous filling operation, such as shown in the copending U.S. Pat. application of Fritz Schumann and Erich Edler, Ser. No. 689,458, filed Dec. 11, 1967, now U.S. Pat. No. 3,613,175 so that a filled container must be shifted away from the filling device and an empty container shifted into place rapidly and accurately. Conventional shifting apparatus includes an arm or a forked shifter which engages a container to push it from the filling station. Such shifter is then swung upward out of the container path and returned to its starting position for shifting the next filled container. Because the filled sliver containers are large and heavy, the shifter must be pressed firmly against such container to provide a sufficiently large shifting force. If the container is misshapen, it is difficult to swing the shifting arm or fork upward without exerting considerable force and without danger of tipping the container.

It is a principal object of the present invention to provide shifting apparatus which can be backed off from engagement with the container before it is swung out of the container path.

Another important object is to provide such apparatus which can readily and economically be used in modifying conventional shifting apparatus.

FIG. 1 is a schematic side elevation of container-shifting apparatus of the present invention.

FIG. 2 is a top plan of the shifting apparatus in one position and FIG. 3 is a similar view showing the apparatus in a different position, parts being broken away in both views.

FIG. 4 is a top plan of another type of shifting apparatus to which the present invention may be adapted and FIG. 5 is a similar view with parts in different relationship. FIG. 6 is a perspective of a detail of FIG. 5.

In FIG. 1 a filled container 2 has been shifted from one location at the fiber-sliver-supply station 1 to a second location remote from the station and an empty container 3 has been shifted into place. A carriage 7 carrying shifting arms 6 and 61 is reciprocated by a chain 5 driven by motor 4.

As shown in FIG. 2, chain 5 carries a pin 51 which extends into channel 71 on the carriage 7 to drive such carriage for reciprocation relative to the container-filling station 1. An arm 6 or 61 engages a container 2 or 3 at one limiting position and pushes the container forward to the other limiting position. After containers 2 and 3 have been advanced to the positions shown in FIGS. 1, 2 and 3, conventionally motor 4 is de-energized with the shifting arms in the position shown in FIG. 2, arm 61 being in firm contact with the side of the container. A motor 8 is then energized to lift arms 6 and 61 by swinging them upward out of the container path. If the container is misshapen, has an irregular side engaged by arm 61 or is tilted as shown in FIG. 1, arm 61 could be swung upward only if the arm-swinging shaft developed substantial torque and the container may teeter or tip as the arm is raised. If, however, arm 61 is backed away from the container a fractional distance T toward its first limiting position before it is swung upward, such arm can swing freely. As shown best in FIGS. 2 and 3, arms 6 and 61 embrace the container, but are spaced apart sufficiently so that, when arm 61 is backed off from container engagement, the

arm 6 also will be spaced at least a distance T from the container.

The positions of drive pin 51, corresponding to the positions of arm 61 in FIGS. 2 and 3, are indicated in FIG. 1 at I and II, respectively. As indicated, backing off of arm 61 is effected by overtravel of pin 51 beyond the point I of maximum travel. Although such overtravel might be effected by the inertia of motor 4, its shaft and chain 5 after de-energization of such motor, it is preferred that such overtravel be positively controlled. The motor control circuit of conventional shifting apparatus can be modified for this purpose by changing the motor cutoff switch in various ways. For example, the drive pin 51 can actuate a limit switch which is located beyond point I, shown in FIG. 1, in the direction of chain travel. Alternatively a contact movable with carriage 7 may engage a fixed contact 9 on the carriage frame in which case the carriage and fixed contacts are of a length to remain in motor-driving engagement until the carriage moves into its extreme forward position, reverses and moves backward a distance T. One of such contacts might be a brush and the other an elongated contact surface which are slidably engageable for a predetermined course of the carriage. The motor would be de-energized upon disengagement of the relatively slidable contacts.

When motor 4 is de-energized, motor 8 is simultaneously energized to swing arms 6 and 61 upward out of the container path. Motor 4 is then re-energized to reverse carriage 7 and return it to its extreme rearward position in which forward arms 6 and 61 can be swung downward to embrace container 3 and the rearward arms can embrace an empty container. In such rearward carriage position, motors 4 and 8 are de-energized so that the arms may fall by gravity into their container-embracing relationship.

The method of backing off a shifting arm or fork can be used with other forms of container-shifting devices in which the shifting means are swung out of the path along which a container is shifted. Another type of shifter is shown in FIGS. 4, 5 and 6 in which the containers 21, 31 and 32 are advanced in an arcuate path by arms 62 and 63.

The shifting arms are carried by a rotating shaft 64 to which is fixed a crank disk 65. A pin 66 connects one end of a connecting rod 67 to such disk. The opposite end of the connecting rod is connected to crankpin 55 and is driven by motor 41 through crankshaft 53 and crank arm 54. Referring to FIG. 5, the shifting arms are in container-engaging position, as shown in full lines, when the crankpin 55 is in dead center position I. The arms can be backed off from engagement with their respective containers through a distance T by continuing rotation of crank 54 until the crankpin is in position II, as indicated in broken lines in FIG. 5. Arms 62 and 63 can then be lifted freely upward in a known manner regardless of the container shape or attitude.

Alternatively, motor 41 can be stopped with the crankpin in its dead center position I and a compression spring 57, having one end mounted by fixed bracket 56 and the other end engageable by shifting arm 62, presses such arm away from its container when the drive motor is de-energized. Such arm movement will effect rotation of the arm-mounting shaft 64 to swing about the shaft axis simultaneously all of the arms carried by such shaft. In this instance it would be desirable to provide a clutch K shown in FIG. 6 be-

tween motor 41 and the crankshaft 53 for crank 54 disengageable by de-energization of the motor control circuit to permit the crank assembly to rotate freely in response to spring pressure. Instead of a compression spring 57 a torsion spring could be provided on arm mounting shaft 64 or on crankshaft 53, for example, to effect backing off of the shifting arm.

I claim:

1. In apparatus for shifting a container, shifting means for moving such a container and movable in one direction along a container-moving path in engagement with the container to a limiting position, the improvement comprising means guiding movement of such shifting means along such container-moving path both to such limiting position and reversely away from such limiting position for a short distance sufficient to withdraw the shifting means from engagement with the moved container, drive means for moving the shifting means along such container-moving path in both directions, control means for energizing the drive means to advance the shifting means to such limiting position and for de-energizing such drive means only after the shifting means has been withdrawn from such limiting

position sufficiently to be disengaged from the container, means for moving the shifting means after having been disengaged from the container generally in a plane disposed transversely of such container-moving path until the shifting means have been withdrawn from such path, and means for thereafter returning the shifting means to a position for engaging and moving a succeeding container.

2. The apparatus defined in claim 4, in which the drive means includes a motor and connecting means connecting said motor and the shifting means, and the control means includes limit switch means engageable by said connecting means for deenergizing said motor when the shifting means has been moved reversely away from such limiting position through such short distance.

3. The apparatus defined in claim 4, in which the control means includes fixed switch contact means and switch contact means movable with the shifting means, said fixed and movable switch contact means being relatively slidably engageable during a predetermined course of the shifting means.
